UNITED STATES PATENT OFFICE.

EDWIN O. READ, OF NEW YORK, N. Y.

SASH-FASTENER.

SPECIFICATION forming part of Letters Patent No. 531,647, dated January 1, 1895.

Application filed December 7, 1893. Serial No. 492,986. (No model.)

To all whom it may concern:

Be it known that I, EDWIN O. READ, a citizen of the United States, and a resident of New York, in the county of New York, State of New York, have invented a certain new and useful Improvement in Sash-Fasteners, of which the following is a specification.

My invention relates to improvements in window catches, and it is the purpose of the improvement to provide a catch which shall combine a high degree of security with simple construction, and shall be capable of ready application to windows without marring the frame or casing.

15 The device is especially adapted to use with balanced windows, and an essential feature of the invention consists in equipping the catch with two arms and two bolt heads which enter separate sockets in the casing. 20 The two arms are arranged one to either side of the sash cord, and are connected by an arched bar which spans the cord. This arrangement renders it practically impossible to jar the catch loose from its sockets, for experiment shows that even if one of the heads could be jarred loose from the socket, it is impracticable to simultaneously jar both heads loose, for the two heads of the catch and the two sockets therefor being at opposite 30 sides of the sash cord and therefore some distance apart, and, also, the heads having a nice fit in the sockets, the shaking of the window sash in the effort to dislodge the catch will turn the catch a little out of true and cause 35 one or the other of the heads to bind against the edge of its respective socket. The aforesaid arrangement is novel in the art, and an important feature of this invention.

Referring to the drawings which accompany the specification to aid the description, Figure 1 is a representation, partly in broken lines of a window with the catch applied and locked. Fig. 2 is a perspective view on a large scale of the catch and socket plate. 45 Figs. 3 and 4 are respectively a side and a front elevation of the catch, and Fig. 5 is a top view of the same. Figs. 6 and 7 are respectively a face view and a section of the socket plate. 50 The scale of Figs. 2, 3, 4, 5, 6, and 7 is the same.

A, B being respectively the lower and upper sashes, the catch C, being preferably screwed on the top of the former, consists of 55 a base plate c, slotted at d to span the sash

cord, and provided with ears e, e, on which are hinged the arms f, g of the catch proper, arranged one to either side of the sash cord H, and connected by the arched bar h, which serves as a finger piece to operate the catch. 60 At their upper ends the arms f, g are respectively equipped with horizontal bolt heads j, k, adapted to fit easily in independent sockets l, m, in the plate M which is screwed in the casing, as shown.

To raise the lower sash the catch is drawn down by means of the bar h. If it is desired that the window shall be secured at various heights, then one or more additional socket plates, as M' are screwed in the casing at the 70 desired height to engage the heads of the catch, as hereinbefore described. It will be understood that a similar catch may be employed at each side of the window, although a catch at only one side is sufficient.

The drawings show the arms f, g as merely pivoted to the ears e, e of the plate c, without springs, since I find that when the pintle E' has a nice fit in the hinge of the catch it is impossible to detach the bolt heads j, k from 80 the sockets l, n, however violently the sashes be shaken; but if it is desired, springs of any suitable construction can be combined with the arms f, g or with the hinges of the catch, to press the aforesaid bolt heads into said 85 sockets and further resist dislodgment.

Now, having described my improvements, I claim as my invention—

In a sash fastener, the combination of a base plate c, provided at its front end with 90 the slot d and with the ears e, e to each side of said slot, arms f, g spaced to admit the sash cord between them and pivoted at their lower ends to said ears e, e, an arched bar h connecting said arms f, g, and adapted to span the 95 sash cord and together with the slot d form a runway therefor, heads on the upper ends of each of said arms f, g, and independent sockets for each of said heads adapted to be secured to the window sash, substantially as 100 described.

In testimony that I claim the foregoing as my invention I have signed my name, in presence of two witnesses, this 21st day of November, 1893.

EDWIN O. READ.
